UNITED STATES PATENT OFFICE.

KONSTANTY DOBROWOLSKI, OF NEW YORK, N. Y.

WRENCH.

1,072,101.

Specification of Letters Patent. Patented Sept. 2, 1913.

Application filed April 18, 1913. Serial No. 761,866.

To all whom it may concern:

Be it known that I, KONSTANTY DOBROWOLSKI, a subject of the Czar of Russia, residing at New York city, borough of Brooklyn, county of Kings, State of New York, have invented certain new and useful Improvements in Wrenches, of which the following is a full, clear, and exact description.

This invention relates to an improvement in wrenches, the object being to provide a combination wrench adapted for use either as a pipe wrench or as an ordinary wrench.

My improved wrench is provided with reversible jaw-members, one side of each jaw-member being plain, another side being serrated or provided with teeth.

My improved wrench has other features of improvement, all of which I will now proceed to describe in detail, and the novel features of which I will point out in the appended claim, reference being had to the accompanying drawings, forming part hereof, wherein:

Figure 1 is a side view of my improved wrench, partly in section; Fig. 2 is a top plan view thereof, partly in section; Fig. 3 is an enlarged side view partly in section of the adjustable jaw-member; Fig. 4 is a detail sectional plan view, the section being taken on a line 4—4 in Fig. 3; Fig. 5 is a detail perspective view of one of the jaw-blocks; Fig. 6 is an enlarged detail elevation of the clutch-member of the wrench; Fig. 7 is a longitudinal sectional view thereof; Fig. 8 is an enlarged side elevation of the adjustable wrench member showing the side opposite to that illustrated in Fig. 3; Fig. 9 is a cross-sectional view, the section being taken on a line 9—9 in Fig. 2; and Fig. 10 is a similar view, the section being taken on a line 10—10 in Fig. 1.

As herein illustrated my improved wrench consists of a handle comprising channeled members 1 and 2 which at one end are provided with heads 3 which when the handle members are assembled serve as a retaining element for a jaw-block 4. The block 4 is provided with guideways 5 which receive guides 6, carried by the heads 3, within the pocket 7. Within the channel 8 of the handle I slidably mount the rectangular shank 9 of an adjustable jaw-member which carries a head 10 provided with a pocket 11. Within the pocket 11 I removably mount a jaw-block 12, the said

block being held in position by a pin 13 which passes through the top 14 of the head 3, the block 12, and into a socket 15 in the shank 9. The pin 13 is held in place by a set screw 16. To place a tension on the block 12 and also to hold it square relative to the block 4, I employ a spring 17 which is secured to the shank by a set-screw 18. The pin 13 is provided with an opening 20 by which means, in connection with a special tool 21, the said pin can be removed. When not in use the tool 21 is held in a recess 22 in the shank 3 (see Fig. 3). The tool 22 is held in the shank by the wall 23 of the handle member 1, as shown by dotted lines in Fig. 2. To get at the tool, the adjustable jaw-member will be pulled out enough to allow the tool to be taken out of its recess. Normally or rather for ordinary use the adjustable jaw-member will never be extended enough to expose the tool to view, and consequently the tool will always be carried by the wrench, when not in use, and will therefore always be handy when needed.

As can be seen in Fig. 5 the jaw-member is provided with a plain face 24 and a serrated face 25, the face 24 being used for nuts, for instance, and the face 25 for pipes. The block 12 is also provided with a plain face 26 and a serrated face 27, for the same purpose. To position the blocks to adapt the wrench for nuts or pipes the blocks 4 and 12 will be reversed. By removing the screw 28 the block 4 can be removed and reversed, the screw being again tightened to hold the block. By removing the pin 13, the block 12 can be removed and reversed. To remove the pin 13 I make use of the tool 21, which is provided with a pointed portion 29 which can be inserted in the opening 20, at which time the pin 12 can be removed after the set-screw 16 has been slackened off or removed. To manipulate the screws 28 and 16, I use the screw-driver end 30' of the said tool 22.

To hold the adjustable jaw-member in an adjusted position to suit a given size nut or pipe, I make use of a special clamp which engages the threaded spindle 29 carried by the shank 9, and which is located in the bored portion 30 of the handle. As can be seen in Fig. 2, the clamp, indicated by 31 Fig. 1, can be manipulated exteriorly of the handle and its function is to grip the threaded spindle and hold the adjustable jaw-member rigid after adjustment. The clamp

31 is fitted in a pocket 32 in the handle and will not have any end lash.

Referring to Figs. 6 and 7, the clamp or clutch of the wrench consists of the members 33 and 34, each of which is provided with rounded faces or edges 35 and 36. One end of each clamp or clutch-member 33 and 34 is flared as at 37, one of said members being provided with a leaf-spring 38. Said 10 clamp-members are prevented from separating longitudinally by means of a tongue 39 and socket 40.

As can be seen in Fig. 7, the clutch members 33 and 34 are threaded; as at 41, 15 throughout a portion of the length, the said threads being adapted to engage the threads on the spindle 29 when the clutch-members are forced together as in Fig. 6 by means of a slidable clamping ring 42 and manipulating plate 43. When the ring 42 20 and plate 43 occupy a position at the left end of the clamp members (as in Fig. 6) the adjustable jaw-member 50 will be held against movement, but when the said plate and ring are moved to the right (as in Fig. 7) the 25 adjustable jaw-member can be moved longitudinally of the handle, for the reason that the teeth 41 will be caused to leave the teeth of the spindle. When the ring 42 and plate 30 43 are moved to the right the ring 42 will strike the spring 38 and press it downwardly, the tongue 39 and socket 40 being the pivot point, the ring and plate passing over the spring 38. By referring to Figs. 35 6 and 7, it will be seen that the leaf-spring 38, which is mounted upon the clamp member 33, is provided with a downwardly turned end, adapted to enter a recess 33^a in

the clamp member 33, the object of this leaf-spring being to lock the ring 42 and adjacent follower plate 43 in the clamped position (see Fig. 6). To release the ring and follower plate, the said leaf-spring 38 is depressed, whereby the ring and plate are free to be moved. Stops 44 are provided to limit 45 the left hand movement of the plate and ring. To prevent the adjustable jaw-member from being withdrawn from the handle, I provide a stop 44^a which works in a groove 45 in the shank 9 (see Figs. 8 and 9). 50 Should the adjustable jaw-member become jammed, a rod or other implement can be passed through the opening 46 in the end of the handle and knocked against the end of the spindle 29. 55

Having now described my invention in detail, what I claim and desire to secure by Letters Patent is:

A wrench consisting of a handle, a jaw-member carried thereby, a slidable shank 60 carried by said handle, a jaw member carried thereby, a clamp carried by said handle adapted to engage said shank, said clamp comprising a plurality of members, a ring surrounding said members, and a leaf-spring 65 carried by one of said clamp members, the leaf-spring carrying clamp member being provided with a recess, said leaf-spring having an inturned end adapted, when depressed, to enter said recess. 70

Signed at New York city, N. Y., this 16th day of April, 1913.

KONSTANTY DOBROWOLSKI.
